UNITED STATES PATENT OFFICE.

EDWARD A. CONNER, OF BRIDGEPORT, CONNECTICUT, ASSIGNOR TO AMERICAN CHAIN COMPANY, INC., A CORPORATION OF NEW YORK.

CABLE-MAKING MACHINE.

Application filed October 27, 1922. Serial No. 597,271.

To all whom it may concern:

Be it known that I, EDWARD A. CONNER, a citizen of the United States, residing at Bridgeport, in the county of Fairfield, State 5 of Connecticut, have invented certain new and useful Improvements in Cable-Making Machines, of which the following, taken in connection with the accompanying drawings, is a specification.

- 10 In my copending application for cable-making machines filed in the United States Patent Office July 10, 1922, Serial Number 574,103, I describe a process of making cable, or strands for cable, characterized by the 15 fact that, prior to laying, the component wires or strands are formed into helices of suitable dimensions without angular distortion of the strands or wires on their axes. In other words, the process described in the 20 application referred to comprises a substantially pure bending operation unaccompanied by axial twisting of the individual wires or strands.

By way of explanation of the foregoing 25 statement, it is to be noted that, following the most common method of preparing strands for cable, as also of forming the strands into cable, each component wire or strand is carried about the core in such 30 manner that it is not restricted to its natural tendency to merely bend about the core, but on the contrary, the forming operation is such that, in addition to bending about the core, the wire itself is twisted on its axis 35 approximately one revolution to every convolution of the helix. There are, therefore, at least two sources from which permanent internal distortions are created; namely, the bending of the wire about the core, and the 40 twisting of it on its own axis. To explain in another way, the strands or wires surrounding the core are bent upon a line which, previous to the bending, constituted a helix on the surface of the wire. To restore 45 the wires to its original internal condition two operations, considering the matter analytically, would be necessary; one consisting of an "unbending" operation, and the other consisting of an "untwisting" operation. So 50 far as the completed cable is concerned the bending operation is of course necessary in order to give it the desired form. On the other hand the twisting operation is necessary only for the purpose of giving the

strands or wires a sufficient set to cause them 55 to hug the core closely.

The process described in my copending application above mentioned eliminates the twisting operation by forming the strands into helices prior to laying them on the 60 cable; and in carrying out the process the strands are bent to shape upon a form which by merely bending will produce the necessary set to cause them to hug the core closely. The specific means which I employ in 65 carrying out the process of that application consists of a preforming nozzle, that is to say, a die which is provided with a passage in the form of a helix of suitable diameter and pitch to bring the wires to the proper set 70 to closely hug the particular core which may be used and to lie closely thereon with respect to each other.

The machine which I describe in the application above referred to for the purpose 75 of carrying out this process is characterized among other things by the fact that it consists of a plurality of separate units, each of which is adapted to preform and lay a single 80 wire or strand. The units are arranged in tandem formation, and each unit takes care of a single wire, the wires being laid on the cable in succession as the core is drawn through the several units. While this construction carries out the process effectively, 85 it involves the use of a multiplicity of similar parts and is, under some conditions, particularly lack of sufficient floor space, somewhat inconvenient; and on account of its length cannot conveniently be operated in any other 90 than a horizontal position.

The object of the present invention is a construction for a cable-making machine which involves in its operation the forming 95 of the wires or strands into helices before laying them in position to constitute component parts of the cable, and which shall also at the same time eliminate the twisting above referred to and thus avoid the resulting objections described above.

Another object is to provide a machine 100 which will perform the ultimate functions of the machine described in my application referred to and which shall at the same time make use of a single preforming head, and 105 for the purpose of laying a single envelope of wires or strands make use of a single flyer only. This construction makes possible a

machine of relatively reduced dimensions occupying relatively little floor space and being capable of operation in a vertical position as well as horizontal.

5 Another object of my invention is to provide a machine characterized as described in the foregoing paragraph in which provision is made for readily winding depleted spools and substituting such rewound 10 spools for other depleted spools.

Other objects of the invention will appear in the description of the machine of the present application and its functions and mode of operation.

15 I will describe my invention and its several embodiments by first considering the simpler form shown in Figure 1. For purpose of description, the machine of Figure 1 may be regarded as composed of two units 20 designated respectively as A and B. The unit A is adapted to form a strand consisting of a core surrounded by six enveloping wires or strands, this particular number of wires or strands being selected merely because it conforms to conventional practice. 25 It is to be understood, however, that the number of strands is by no means invariable, it being, of course, permissible to use any number of strands with or without a 30 core wire which can be properly utilized. The strand formed by the unit A then serves as a core which is enveloped by the unit B with other wires or strands. As actually shown in the machine of Figure 1, and, 35 in fact, of all of the figures, the machine is adapted to envelope the strand completed by unit A with 12 wires. Likewise as in the case of unit A any number of wires may be selected for unit B by properly modifying 40 their cross-sectional dimensions. It may further be pointed out that, even in the case of unit B, strands as distinguished from solid wires may be used to envelope the core if desired.

45 Figure 1 is a view in side elevation of a complete machine composed of two units indicated respectively by the letters A and B.

Figure 2 is a vertical longitudinal section of one of the mountings of the spindle of 50 the unit A.

Figure 3 is a vertical longitudinal section of the mountings of the spindle of unit B.

Figure 4 is a vertical side elevation of a modification of the machine in which is incorporated an arrangement for the ready interchange of wire supply spools. This form of machine is also shown as embodying two units, indicated respectively by the letters A' and B'.

Figure 16 is a view on the line 16—16 of Figure 4.

Figure 17 is a view showing the means for engaging and disengaging the complementary parts of the wire supply spools. 90

Referring then to unit A, Figure 1, support for the operating parts may consist of standards 1 and 2 mounted on any suitable foundation. Power may be imparted to the machine in any suitable manner through the medium of the gear 3 carried by the lay shaft 4, the lay shaft 4 carrying the gear 5 and also the gear 6, the latter, namely, the gear 6, being used to communicate power to unit B, as will be hereinafter more particularly referred to. The gear 5 meshes with the gear 7 which is merely an idler and is used merely to transmit power to the gear 8 mounted on the spindle 9, which in turn is mounted in suitable bearings in the standards 1 and 2 and is provided with a hollow core. In order to permit sliding of the spindle through its bearing in the standards 1 and 2, for the purpose of removing 95 depleted spools and replacing them with full spools, the gear 8 is made easily removable as shown in Figure 2, being splined on the spindle 9 and locked thereon by a small hand wheel 10 screwed on to the end of the shaft. The journal which turns in the bearing in standard 1 is of conventional form 100 and requires no further description. The journal which turns in the bearing in standard 2, however, is of a type particularly adapted for use in the machine, and for an understanding of it reference is made to Figures 8 and 9. Referring first to Figure 8, the spindle 9 is provided with an enlargement 11 which in turn is sleeved in a bushing 12 which, in combination with the part 11, constitutes the head of the flyer or rotor, 105 which will be further described in detail. The part 11 is provided with six preforming dies 13 spaced at substantially equal angles 115 with respect to the spindle. The preform-

100

105

110

115

120

125

130

ing dies 13 are provided with helical grooves through which the wires are drawn and consequently formed into helices before being wrapped about the core to constitute component parts of a completed strand. To prevent the head from sliding out of its bearing and also to make the part 11 non-rotatable but at the same time readily removable with respect to the bushing 12 a flange 12^a 5 is provided and the parts 11 and 12 are retained together by the screws 12^b. This construction together with the removable gear of Figure 2 makes it possible to readily withdraw the spindle from its bearing in 10 15 the standard 1 for the removal and replacement of spools.

The flyer for the unit A consists of the two arms 14 and 15 integrally or otherwise rigidly connected with the bushing 12 and 20 extending substantially parallel with the spindle 9 and diametrically opposite to each other. Altho Figure 6 is intended primarily to illustrate the form of the machine in which is incorporated provision for winding 25 reserve wire supply spools, nevertheless, it satisfactorily shows the construction of the arm 14 of Figure 1; and for an understanding of the construction of these arms and the travel of wire from the spools through 30 the dies, reference may be had to Figure 6 in connection with Figure 1. The arm 14 is provided with three swiveled pulleys 16, 17 and 18 located respectively in such positions that they will be respectively opposite 35 alternate wire spools carried by the spindle 9. The arm 15 is likewise provided with three swiveled pulleys 19, 20 and 21, (see Fig. 1) these, however, being so located that they occupy positions opposite the remaining 40 three spools respectively. The advantage of this arrangement lies in the fact that by means of it approximate uniform distribution of the points of application of the tension in the wires is secured as the 45 wires are drawn from the spools, and even balance of the flyer is secured. The pulleys 16, 17 and 18 and also the pulleys 19, 20 and 21 are swiveled in order that as the 50 diameters of the coils of wire are reduced as the wire is drawn off, the planes of these pulleys will be approximately tangential to the coils of wire and the wire will run evenly over them. After the wires travel over the 55 pulleys 16, 17 and 18 they next travel on the pulleys 22, 23 and 24 and thence through the upper three dies 13 (see Fig. 7) whereby they are formed into helices. A similar arrangement is provided for the wires which 60 travel over the pulleys 19, 20 and 21, these traveling on the pulleys 28 and through the lower three dies 13 (see Fig. 7). The 65 wire supply spools indicated by the numeral 30 are rotatably carried on the spindle 9, and axial motion of them along the spindle 9 is prevented by the collar 31. Since the

spools are rotatably mounted on the spindle 9, some sort of means is desirable for damping their free motion thereon, and such means may consist of the brakes 32 carried by one of the arms, as, for instance, arm 15. 70 These brakes bear on the flanges of the spools, each brake preferably operating on two spools. The core wire or strand 33 may be drawn from any suitable source, such as a spool or reel frictionally controlled to keep 75 the core taut. In the case of the particular construction of Figure 1 which incorporates a twelve strand unit B, the power for drawing the core 33 through the spindle 9 is applied to the cable at a point beyond the 80 unit B. This drawing mechanism is not illustrated, as any conventional type may be used, it being only necessary that its speed be coordinated with the speed of rotation of one of the flyers, the speeds of the flyers, of 85 course, being coordinated with one another.

It will therefore be obvious that, as power is supplied to the pulley 3 and the lay shaft is rotated, the spindle 9 and with it the flyer is rotated; and that as the cable is 90 drawn, wire is drawn from the spools through the various pulleys and dies, and that as it emerges from the dies each wire is in the form a helix. Consequently, it is in a form ready to lay easily and without resistance on the core 33. Merely for the purpose of steadyng the arms 14 and 15, their free ends may be provided with rollers 34 which travel on the annular track 35, this arrangement being desirable merely 95 to prevent them from flying out or otherwise running irregularly when the machine is operated at the high speeds for which it is intended.

When it is necessary to renew the supply 105 of wire, the hand wheel 10 may be unscrewed, the gear 8 and the screws 12^b removed. The shaft may then be partially withdrawn in the direction of the arrow C until it is sufficiently clear of the bearing 110 in the standard 1 to permit the removal of the spools. The spools may then be removed and full ones substituted and the shaft restored to its original position for the resumption of the laying operation. 115

The construction of unit B, Figure 1, is similar to that of unit A except for such modifications as make it adaptable for operating on twelve wires or strands, and also except for the direction and relative speed 120 of its rotation. Even these differences may be considered as immaterial to the essence of the invention, it being entirely permissible, as is more or less common practice, not only to vary the number of wires constituting the second envelope but also to wind the second envelope of wires in the same angular direction as the first, and it also being permissible, if desired, to wind them 125 in helices of the same pitch. The respective 130

pitches of the several convolutions are merely functions of the diameters of wires or strands and modifications of relative speeds of the flyers may be easily made accordingly.

5 As the wires emerging from the dies of unit A become formed into a strand such as indicated by the numeral 37, the strand thus formed becomes a core for unit B. Unit B is driven by the gear 38 which in 10 turn is driven by the gear 39. Between the gear 39 and gear 6 on the lay shaft 4 is interposed the gear 40 which serves to rotate the flyer of unit B in an angular direction opposite to that of the flyer of unit A, 15 thus winding the second envelope of wires or strands in a direction opposite to the first envelope.

Unit B may be best described by comparing it with unit A. In order to accommodate 20 the considerably greater number of wires, the flyer is preferably provided with three arms 41, each of these arms taking care of four wires and, consequently, four spools. The head is provided with twelve dies 42 25 (see Figs. 12 and 14) and there are twelve swivel pulleys 43 and twelve pulleys 44 which guide the wires or strands into the dies or nozzles. The spindle 45 of the unit B is hollow as in the case of unit A, so that 30 the strand formed by unit A can pass through it and serve as a core, as in the case of the wire or strand 33 in unit A. To properly balance the weight of the flyer, each arm may take care of every fourth 35 spool. A substantially similar arrangement may be provided for removing the spools as shown in Figure 3. The gear 38 on the spindle 45 may be splined or otherwise carried by the spindle, and may be retained thereon by a nut 46 and washer 47. The head may be provided with the flange 47^a and the screws 47^b. When it is desired 40 to remove the spools, the nut 46, the washer 47 and screws 47^b gear 38 may be removed 45 and the spindle partially withdrawn in the direction of the arrow D, whereupon the spools may be removed and replenished ones substituted for them.

It has been heretofore mentioned that it 50 may be desirable to rotate unit B at a lesser speed than unit A. This, of course, may easily be done by properly proportioning the ratio of the train of gears between gear 6 and gear 38. As the flyer of unit B would 55 ordinarily be of considerably greater length than that of unit A, it is advisable to provide two annular tracks 48 and 49 instead of one within which it may be rotated.

The embodiment of the invention shown 60 in side view in Figure 4 may, like that of Figure 1, be considered for purposes of description as being composed of two units designated respectively A' and B', the unit A' performing among others the functions 65 of unit A of Figure 1, and unit B' perform-

ing, among others, similar functions to those performed by unit B. In the construction of Figure 4, however, there is incorporated in each unit provision for winding reserve wire supply spools at the same time that the 70 wire spools are delivering wire to be laid in the cable in process of manufacture. In addition to the last named function the construction of Figure 4 is such that the empty 75 spools may be readily removed from the shaft and the reserve spools readily put in place of them. Like the construction of Figure 1, the construction of Figure 4 in the specific embodiment shown is capable of winding a first envelope of six wires or 80 strands, and either with or without a core, and then winding a second envelope of twelve strands about the six strands, the latter serving as a core for the twelve strands. 85 As in the case of Figure 1, however, it is to be noted that the specific number of strands which each unit is capable of winding is merely a matter of selection governed by the requirements of the particular case, and that consequently the machine may be 90 properly modified without departing from the spirit of my invention so that any desired number of wires or strands may be utilized.

Referring then to unit A' which operates 95 on six wires or strands, and more particularly referring to Figures 5 and 6 which are sectional and plan views respectively of this unit, suitable standards 50 and 51 are provided, these being mounted on any suitable foundation; and in these standards 100 is rotatably mounted the lay shaft 52 provided with the gear 53 and also the gear 54 whereby power may be imparted to the machine. In a bearing in the standard 50 is rotatably mounted the bushing 55 which 105 serves as an axle for the gear 56 and which terminates in the outer clutch collar 57, the latter being faced with friction lining 58 in the usual manner. The bushing 55 110 serves as a bearing for the spindle 59 and the spindle 59 is provided with the gear 60 to which power is imparted by the gear 53 through the medium of the gear 61. The gear 61 is rigidly mounted with respect to 115 the gear 62 so that the result is that as the gear 53 rotates both the spindle 59 and the clutch member 57 rotate, the latter, however, rotating at the lesser speed by reason 120 of the difference in the ratios of the respective gears which drive them.

The spindle 59 instead of being of uniform diameter as in the case of the construction of 51 is enlarged from the point 63; that is to say, at such a point that the 125 smaller portion is long enough to accommodate six spools of a suitable size to be used with the machine. On the smaller portion of the spindle 59 is rotatably mounted a sleeve 64 provided with a spline 65 and hav- 130

ing rigid connection with the inner clutch member 66. The spools 67, six in number, are in turn mounted upon the sleeve 64 and splined thereon by the spline 65, but not so 5 tightly but that they can be readily caused to slide along the sleeve and thence on the larger portion of the spindle. It is to be noted that the sleeve 64 is made of the same diameter as the larger portion of the spindle 10 59 so that as the spools 67 are caused to slide along the sleeve they move unimpeded upon the larger portion of the spindle.

The opposite end of the spindle is mounted in the same manner as is the corresponding 15 end of the spindle of Figure 1; that is to say (see Figs. 12, 13 and 14), the spindle 59 is rigidly or otherwise fixedly mounted in the enlarged portion 68 in which are mounted twelve dies 42 arranged about the 20 bore 70 of the spindle. The part 68 is in turn rigidly mounted in the bushing 71 of the flyer which is provided with the arms 72, 72. The arms 72 are similar to the arms 14 and 15 of Figure 1 and need no further 25 description. As in the case of the construction of Figure 1 they are provided with rolls 73 traveling on the annular track 74 which prevents them from flying outwardly when the flyer is rotated to a dangerous or 30 undesirable extent. Brake shoes 75 are provided as in the case of the construction of Figure 1.

To make full use of this particular type 35 of machine it is desirable to make use of wire spools that can be readily engaged with and removed from the shaft. A suitable spool construction for this purpose has been described in detail in my now pending application Serial No. 574,103, filed July 40 10, 1922, hereinbefore referred to, and requires but brief description. Referring to Figure 17 the spool may be composed of two complementary parts 76 and 77, the plane of division preferably passing through the 45 axis of the spool. One of these parts, for instance, the part 77, may be provided with lugs 78 which are formed to engage the lugs 79 in the part 76, and the two parts of the spool may, by interlocking the lugs 78 with 50 the lugs 79, be firmly retained together on the spindle. In order to reduce friction, it is desirable to provide the spools with lateral bearing surfaces 80.

As hereinbefore stated, one of the spool 55 parts is provided with a groove adapted to fit on the spline 65 of the sleeve 64. The consequence is that while the spools are prevented from rotating on the sleeve 65 they may freely rotate on the larger portion of the spindle 59.

In utilizing this feature of my invention 60 in connection with the machine now being described a proper method would be as follows: Six spools would be separated and 65 then interlocked together over the sleeve 65.

The machine would then be set in motion and wire or strand wound on these spools from any convenient source. When sufficient wire had been wound upon them they would then be forced along the sleeve 65, 70 one by one, or all together, as desired, and thence on to the large portion of the spindle 59 in the position occupied by the spools 81. The replenished spools are then in proper position for the wire to be drawn off for 75 the manufacture of a strand or cable. Then, or, at any time when the machine is at rest, a full complement of empty spools would be placed upon the sleeve 64 and filled with wire or strand in the manner above described. As fast as a complement of spools on the larger portion of the shaft 50 is depleted of wire, they can be removed by disengaging their connecting lugs. In order to prevent the spools from separating both 80 on the sleeve 64 and on the larger portion of the spindle 69 it is desirable to provide a removable collar 82 which may be clamped in any desired position by the set screw 83.

For convenience it is desirable to make 85 provision for automatically throwing the clutch when sufficient wire has been wound upon the reserve spools. Any suitable method may be adopted, such as the bell crank lever 84 pivotally mounted to a fixed portion of the machine at 85 and carrying the roll 86. The arm 87 of this lever may have the usual yoke connection with the inner sliding member 66 of the clutch; and, consequently, when the diameter of the coil 90 of wire on the spool with which it cooperates has attained certain predetermined dimensions, the clutch is thrown and the winding of wire on the reserve spools ceases.

The twelve strand unit B' of the construction in Figure 4 corresponds to the twelve strand unit of the construction shown in 59, but in addition has the modification similar to those described with respect to the unit A' of Figure 4; that is to say, it is made of 105 suitable proportions to accommodate twelve spools instead of six, and the flyer is preferably provided with three arms instead of two by reason of the greater number of wires which it accommodates, and two annular 110 tracks are provided for greater security of operation. Similarly, as in case of the construction of Figure 1, the strand emerging from unit A' is utilized as a core on which the outer envelope of twelve strands is 115 wound by unit B'. As in the case of the construction of Figure 1, the relative directions of rotations of the units A' and B' are not important except to fulfil special requirements. I have, however, shown the arrangement such that the twelve strand unit rotates in a direction opposite to that of the six strand unit; and the mechanism for accomplishing this may be the same as in 120 the case of the construction of Figure 1. 130

Likewise, the power for drawing the cable through the machine is applied at a point in the cable after it emerges from the twelve strand unit; and the finished cable may be 5 wound upon a reel, drum or other suitable container.

Claims:

1. In a cable-making machine, a flyer provided with a plurality of separate means for forming into helices wires subjected to the action of said means prior to laying said wires on the cable.
2. In a cable-making machine, a flyer provided with a plurality of separate preforming nozzles adapted to form into helices wires passing through said nozzles prior to laying said wires on the cable.
3. In a cable-making machine, a flyer provided with a plurality of preforming nozzles arranged on a circle concentric with the axis of rotation of said flyer, said preforming nozzles being adapted to form into helices wires passing therethrough.
4. In a cable-making machine, a flyer provided with a plurality of separate means for forming into helices wires subjected to the action of said means prior to laying said wires on the cable, a spindle on which said flyer is mounted, said flyer also being provided with arms extending substantially parallel with said spindle, and plurality of sources of wire supply.
5. In a cable-making machine, a hollow spindle, a flyer mounted thereon, the head of said flyer being provided with a plurality of preforming nozzles adapted to form wires drawn therethrough into helices and also being provided with arms extending substantially parallel with said spindle and adapted to serve as wire guides, and wire supply spools mounted on said spindle.
6. In a cable-making machine, a hollow spindle, a flyer comprising a head rigidly connected with said spindle and also with arms extending substantially parallel with said spindle, said arms being provided with anti-friction means over which wire can be drawn, a plurality of wire supply spools carried by said spindle and rotatably mounted thereon, and means for damping the free rotation of said spools on said spindle.
7. In a cable-making machine, a spindle, a plurality of wire supply spools mounted rotatably and independently of each other on said spindle, a flyer comprising a head and arms connected thereto, the said head being rigidly connected with said spindle and provided with preforming nozzles, and said arms being provided with anti-friction means over which wire can be drawn from said spools through said preforming nozzles.
8. In a cable-making machine, a rotatably mounted head, a spindle slidably mounted in said head, a flyer rigidly connected with said head, a plurality of preforming nozzles

mounted in said head, said spindle being adapted to carry a plurality of spools rotatably mounted thereon and means for damping the free rotation of said spools on said flyer.

9. In a cable-making machine, a plurality of stranding units each unit comprising a hollow spindle, a head serving as a journal for said spindle and provided with a plurality of helix-forming devices, a flyer rigidly connected with said head and provided with a plurality of wire guiding arms extending substantially parallel with said spindle, and sources of wire supply carried by said spindle.

10. In a cable-making machine, a stranding unit consisting of a hollow spindle, a sleeve on said spindle, said sleeve being adapted to carry a plurality of reserve wire supply spools non-rotatably mounted thereon, and said spindle being also adapted to carry a plurality of wire supply spools rotatably mounted thereon.

11. In a cable-making machine, a stranding unit consisting of a hollow spindle, a sleeve on said spindle, said sleeve being adapted to carry a plurality of reserve wire supply spools non-rotatably mounted thereon, said spindle being also adapted to carry a plurality of wire supply spools rotatably mounted thereon, and means for rotating said sleeve and said spindle independently of each other.

12. In a cable-making machine, a stranding unit consisting of a hollow spindle, a sleeve on said spindle, said sleeve being adapted to carry a plurality of wire supply spools non-rotatably mounted thereon, said spindle being also adapted to carry a plurality of wire supply spools rotatably mounted thereon, means for rotating said sleeve and said spindle, a rotatably mounted head serving as a journal for said spindle, said head being provided with a plurality of helix-forming devices, and a flyer carried by said head.

13. In a cable-making machine, a stranding unit consisting of a hollow spindle, a sleeve on said spindle, said sleeve being adapted to carry a plurality of reserve wire supply spools non-rotatably mounted thereon, said spindle being also adapted to carry a plurality of wire supply spools rotatably mounted thereon, means for rotating said sleeve and said spindle independently of each other, a rotatably mounted head serving as a journal for said spindle, said head being provided with a plurality of helix-forming devices, a flyer carried by said head, said flyer comprising a plurality of arms extending substantially parallel with said spindle over which wire may be drawn, said arms serving as guides for directing said wire through said helix-forming devices.

14. In a machine for making stranded

- cable, a plurality of helix-forming nozzles with their emergent ends substantially in the same plane, sources of wire supply, means for forcing wire from said sources 5 of wire supply through said nozzles, and means for producing relative rotation as between said nozzles and the cable in process of fabrication.
15. In a machine for making stranded cable, a plurality of helix-forming nozzles the emergent ends of which are disposed substantially in the same plane, sources of wire supply, means for forcing wire through said nozzles, and means for producing relative 10 rotation as between said nozzles and the cable in process of fabrication, the speed of said rotation being coordinated with the speed with which said wire is forced through said nozzles.
16. In a machine for making stranded cable, a plurality of helix-forming nozzles the emergent ends of which are disposed substantially in the same plane, sources of wire supply, means for propelling wire 15 through said nozzles, and means for producing relative rotation as between said nozzles and the cable in process of fabrication, the axis of said rotation being in the said cable line.
17. In a machine for making stranded cable, a plurality of helix-forming nozzles, the emergent ends of which are disposed in a plane substantially at right angles to the cable line of the machine, sources of wire supply, means for forcing wire through 20 said nozzles, and means for producing relative rotation as between said nozzles and sources of wire supply on the one hand and the cable in process of fabrication on the other.
18. In a machine for making stranded cable, a plurality of helix-forming nozzles the emergent ends of which are disposed substantially in a plane normal to the cable line of the machine, sources of wire supply, means for forcing wire through said nozzles, means for producing relative rotation as between said nozzles and sources of wire supply on the one hand and the cable in process 25 of fabrication on the other, the speed of said rotation being coordinated with the speed with which the wire is forced through the said nozzles to produce substantially one revolution of said receiving means to each convolution of the helically-formed wire.

In testimony whereof, I have signed this specification.

EDWARD A. CONNER.
